CASKET HANDLING APPARATUS

David A. Collings, Cleveland, Ohio, assignor to
Saul I. Fineman

Application November 20, 1940, Serial No. 366,389

11 Claims.

(Cl. 27—26)

This invention relates to casket handling apparatus, and more particularly to improvements in the parts by which a casket is preliminarily supported in position over the grave prior to lowering of the same.

In apparatus of this character, there is usually provided a rectangular enclosure and supporting structure surrounding the grave and having lowering straps extending transversely of the longitudinal side members of such structure by which the casket may be lowered into the grave. In order to facilitate positioning of the casket over the grave and lowering straps, the use of roller supports extending inwardly of the longitudinal side members has been proposed. Where such roller supports are employed, it is necessary that they be mounted for movement from an operative supporting position under the casket to an inoperative supporting position permitting lowering of the casket into the grave. It is also desirable that mechanism be provided for effecting simultaneous movement of the supports to and from their operative supporting positions.

One of the principal objects of this invention is to provide an improved arrangement of mechanism for moving casket supporting rollers to and fro between operative and inoperative supporting positions.

A further object is to provide a casket supporting device and operating mechanism therefor which may be readily and easily applied to the supporting standards provided with conventional lowering mechanism.

A further object is to provide a casket supporting member pivotally mounted for swinging movement to and fro between operative and inoperative supporting positions with a novel form of actuating mechanism therefor.

A further object is to provide actuating mechanism for a movable supporting member of the character referred to in which there is provided a rockable actuating member which is effective on a single throw or rocking movement thereof to either move the supporting member to or from its operative supporting position.

Other objects and advantages of the invention will become apparent during the course of the following description.

To the accomplishment of the foregoing and related ends, the invention, then, comprises the features hereinafter fully described, and particularly pointed out in the claims, the following description and the annexed drawings setting forth in detail certain illustrative embodiments

of the invention, these being indicative however, of but a few of the various ways in which the principle of the invention may be employed.

In said annexed drawings—

5 Fig. 1 is a top plan view of a casket handling apparatus constructed in accordance with the principles of this invention;

Fig. 2 is a side elevational view of the apparatus shown in Fig. 1;

Fig. 3 is an end elevational view of the apparatus shown in Figs. 1 and 2;

Fig. 4 is a broken away vertical sectional view of a part of the apparatus shown in Fig. 1, illustrating the arrangement of the supporting rollers, and actuating mechanism therefor with the supporting rollers in an operative supporting position;

Fig. 5 is a view similar to Fig. 4, showing the position of the supporting rollers and actuating mechanism therefor after being moved to inoperative supporting position;

Fig. 6 is a sectional view taken substantially on the line 6—6 of Fig. 4;

Fig. 7 is a sectional view taken substantially on the line 7—7 of Fig. 4;

Fig. 8 is a sectional view taken substantially on the line 8—8 of Fig. 2, parts of the apparatus being broken away;

Fig. 9 is a sectional view taken on the line 9—9 of Fig. 8;

Fig. 10 is an enlarged broken away sectional view illustrating the construction of the pivotal connection between the rockable actuating member and the connecting link shown in Figs. 4 and 5; and

Fig. 11 is an end view illustrating a motion reversing connection employed in connection with the mechanism by which simultaneous movement is imparted to all of the supporting rollers.

Referring to Figs. 1, 2 and 3 of the drawings, there is shown a casket supporting and lowering device comprising corner posts 1 having longitudinal supporting members 2 and transverse connecting members 3 extending between the end posts 1 to provide a rectangular supporting structure. The supporting structure is also provided with longitudinal bracing members 4 and transverse bracing members 4'. The members 2, 3, 4 and 4' are preferably telescopically constructed to permit adjustment of the corner posts 1 for various size graves. Lowering straps 5 extend transversely of the supporting structure and have their end portions respectively reeled about the opposite longitudinal

members 2, the supporting structure being provided with conventional lowering mechanism (not shown) for controlling the unreeling of the straps 5 and thereby the lowering movement of the casket carried by the straps. The parts of the apparatus thus far described form no part of this invention other than in combination with the supporting mechanism to be described.

In order to facilitate positioning of the casket over the straps 5 and to support such casket independent of the straps 5, a plurality of frictionless supporting rollers 6 extending inwardly of the supporting members 2 are provided. The supporting rollers 6 are preferably located adjacent the straps 5 and are carried by a collar 7 rotatably mounted on the supporting members 2, the connection of the rollers 6 to the collars 7 being such to permit swinging movement of the rollers 6 with the collars 7 with respect to the supporting members 2.

To effect movement of the supporting rollers 6 from their operative supporting position shown in Fig. 4 to the withdrawn position shown in Fig. 5, each of the supporting rollers 6 is provided with a pivotal connection 8 at its outer end to an actuating member or link 9, the link 9 being provided with a pivotal connection 10 to a rockable actuating member 11 carried by a rock shaft 12 extending longitudinally of the corner posts 1. Each of the supporting members 2 has associated therewith one of the rock shafts 12 which carries all the actuating members 11 for the rollers 6 associated with such supporting member 2. As best shown in Fig. 8, the ends 13 of the rock shafts 12 are rotatably journaled in the end posts 1. The rock shafts 12, similar to the members 2, 3, 4 and 4', are formed of telescopically receivable parts 14 and 15 to permit adjustment of the overall length thereof, in accordance with the position of the corner posts 1. A clamping device 16 is provided for securing the parts 14 and 15 in a fixed position of adjustment. The part 14 is provided with a pivotal connection 17 to the part 13 adjacent the corner posts 1. The pivotal connection 17 permits swinging movement of the part 14 with respect to the corner posts 1 from the position shown in full lines in Figs. 1 and 8, to the position shown in dotted lines upon disassembly of the structure by withdrawal of the part 14 from the part 15. The movement of the parts 14 to the position shown in dotted lines in Fig. 1, provides a more compact structure when the parts are disassembled for shipping from one site to another.

To move the rollers 6 from the operative supporting position shown in Fig. 4 to the withdrawn position shown in Fig. 5, the actuating shaft 12 and actuating member 11 carried thereby, are rocked in a counterclockwise direction from the position shown in Fig. 4 to the position shown in Fig. 5. This rocking movement pulls the pivot pin 10 inwardly toward the corner posts 1, and the link 9 will pivot about the point 8 to cause and permit swinging movement of the rollers 6 from the position shown in Fig. 4 to the position shown in Fig. 5. To move the rollers 6 to their operative supporting position, the member 11 will be rocked in a clockwise direction. By this arrangement, a comparatively short rocking movement of the actuating member 11 in a single direction will be effective to move the supporting rollers 6 to either an operative supporting position or a withdrawn position.

Referring to Figs. 4, 7 and 10, it will be noted that the pivot pin 10 is secured to the actuating member 11, and is engageable in a slot 18 formed in the lower end of the link 9, thereby providing a lost motion connection between the link 9 and actuating member 11. This lost motion connection provided by the pin and slot 10 and 18, is provided to facilitate movement of the parts to the withdrawn position. The actuating member 11 comprises externally threaded end parts 19 and 20 having engagement with an internally threaded adjusting member 21. This construction permits adjustment of the effective length of the actuating member 11 between the shaft 12 and pivot pin 10, in order to adjust the position of the rollers 6 when the parts are in the position shown in Fig. 4. The lost motion connection between the link 9 and actuating member 11 is necessary in order that this adjustment may be had.

The link 9 is preferably constructed from a U-shaped channel having the slots 18 formed in the sides thereof for engagement with the pin 10 and so arranged to provide a part 22 extending inwardly of and engageable with the outer end of the actuating member 11 to limit rocking movement of the member 11 in a clockwise direction. Any tendency of the parts to move beyond the position shown in Fig. 4 will be prevented by engagement of the part 22 with the surface 23 at the end of the actuating member 11, the part 22 fulcruming about the pivot 10 into engagement with the surface 23. The part 22 is provided with a lug 24 engageable in a slot formed in the outer end of the actuating member 11, as best shown in Fig. 10, for limiting outward movement of the link 9 with respect to the actuating member 11. The lug 24 moves into its slot upon movement of the actuating member 11 to the limit of its clockwise movement. Movement of the actuating member 11 in a counterclockwise direction will be prevented by the link 9 moving into engagement with the actuating member 11 upon movement of the parts to the position shown in Fig. 5. In this manner, the rocking movement of the member 11 is limited to movement back and forth between two positions. These two positions, through the link 9, determine the operative and withdrawn positions of the roller 6, and such roller will be moved back and forth between these positions as the member 11 is moved back and forth between its limited positions of rocking movement.

Referring to Figs. 1 and 2, it will be noted that each of the collars 7 carries a pin or roller 25 extending laterally outwardly therefrom in a direction parallel to the supporting members 2. The pins 25 are engageable with the upper surface of the straps 5 and are effective to insure that the belt 5 will always be below the supporting surface of the rollers 6 so as to not hinder movement of the casket to a position over the supporting straps. The pins 25 also function to make the lowering mechanism for the straps 5 available as an additional support for the rollers 6. The pins 25 also operate to cushion the initial lowering movement of the rollers 6 under the weight of the casket when the actuating members 11 are rocked in a counterclockwise direction to shift the weight of the casket to the lowering belt. The pins or rollers 25 also act as a guiding element for the strap 5 when the strap 5 is unreeling with respect to the members

2. to lower the casket and the roller 6 is in the position shown in Fig. 5.

A manual operating lever 26 is secured to one of the shafts or actuating members 12. As best shown in Fig. 11, the ends of the shafts 12 are provided with oppositely positioned arms 27 connected together by an adjustable link 28 in such manner that when one of the shafts 12 is moved in one direction the other shaft 12 will be moved in an opposite direction, to effect simultaneous movements of the rollers 6. It will be apparent that the shaft 12, associated with the side of the supporting structure opposite that shown in Figs. 4 and 5, must be moved in a direction opposite that of the shaft 12 shown in Figs. 4 and 5. The motion reversing connection shown in Fig. 11 enables simultaneous opposite movement of the rocking shafts 12 to effect simultaneous movement of all the supporting rollers to and from their operative supporting positions.

From the foregoing, it will be apparent that there is provided a novel and simplified arrangement of mechanism for moving the rollers 6 from a withdrawn to an operative supporting position. It will also be apparent that the parts 9 and 11 comprise a linkage system which enables a manually operable lever, such as the lever 26, to move the rollers 6 from a withdrawn to an operative supporting position by a single short rocking movement of such lever in one direction from one position to another. It will also be apparent that the simplicity of the actuating mechanism readily enables its application to conventional casket lowering mechanisms with a minimum of expense and without interfering with the operation of the lowering mechanism.

Other modes of applying the principle of my invention may be employed instead of the one explained, change being made as regards the mechanism herein disclosed, provided the means stated by any of the following claims or the equivalent of such stated means be employed.

I, therefore, particularly point out and distinctly claim as my invention:

1. In casket handling apparatus, a support, a casket supporting member pivotally connected to said support for swinging movement with respect thereto from a withdrawn vertical position to an operative horizontal supporting position, a rockable actuating shaft, motion transmitting means operable upon movement of said shaft in one rotational direction to move said supporting member in an opposite rotational direction comprising an actuating member connected to said shaft for movement therewith, and a link having pivotal connections with said actuating and supporting members, and a manually operable lever connected to said shaft for imparting a rocking movement thereto, said motion transmitting means being effective upon a single throw of said lever to move said supporting member from one of its positions to another of its positions.

2. Apparatus as claimed in claim 1 wherein said actuating member and link are provided with interengageable parts at their point of pivotal connection for limiting movement of said actuating member and shaft in one direction, said supporting member being in its operative supporting position when movement of said actuating member by said parts is thus limited.

3. Apparatus as claimed in claim 1 wherein the pivotal connection of said actuating member

with said link is a pin and slot connection permitting relative movement of the point of pivotal connection between such members.

4. Apparatus as claimed in claim 1 wherein the length of said actuating member is adjustable for the purpose of adjusting the operative supporting position of said supporting member with respect to said support.

5. In casket handling apparatus having a pair of parallel supporting bars, a plurality of supporting members connected to each of said bars for swinging movement with respect thereto from a withdrawn vertical position to an operative horizontal supporting position, each of said bars having a rockable actuating shaft associated therewith and parallel thereto, each of said shafts having motion transmitting means operable upon movement of such shaft in one rotational direction to move the supporting members on its associated bar in an opposite rotational direction, said means comprising a separate link pivotally connected to each of said members, and an actuating member pivotally connected to said link and secured to one of said shafts for movement therewith, and common actuating means for both of said shafts comprising a manually operable lever connected to one of said shafts for imparting movement thereto, and a motion reversing connection between said shafts effective to move the same in opposite rotational directions upon movement being imparted to one of said shafts, said motion transmitting means being effective upon a single throw of said lever to actuate said shafts to move all of said supporting members from one of said positions to another of said positions.

6. In a casket lowering device having parallel bars, a temporary support member having a portion thereof rotatably mounted upon one of said bars, a rock shaft extending parallel to and below such one parallel bar, and toggle links connecting said rock shaft with another portion of said temporary support, said links lying between said rock shaft and said one parallel bar when said temporary support extends downwardly in withdrawn position.

7. In a casket lowering device having parallel bars, a temporary support member having a portion thereof rotatably mounted upon one of said bars, a rock shaft extending parallel to and below such one parallel bar, and toggle links connecting said rock shaft with another portion of said temporary support, one of said toggle links overlapping the other in such manner as to form a substantially rigid load bearing connection between said rock shaft and said temporary support, when said temporary support is in operative horizontal position.

8. In a casket lowering device having parallel bars, a temporary support member having a portion thereof rotatably mounted upon one of said bars, a rock shaft extending parallel to and below such one parallel bar, and toggle links connecting said rock shaft with another portion of said temporary support, one of the toggle links being fixedly secured to said rock shaft and oscillating in an upwardly opening arc when said temporary support is moved from operative to inoperative position.

9. In a casket lowering device having parallel bars, a temporary support member having a portion thereof rotatably mounted upon one of said bars, a rock shaft extending parallel to and below such one parallel bar, and toggle links connecting said rock shaft with another portion of said

temporary support, one of the toggle links being fixedly secured to said rock shaft and oscillating in an upwardly opening arc when said temporary support is moved from operative to inoperative position, the other link being freely pivoted upon said temporary support at one end thereof and means at the other end restricting pivotal movement thereof when said toggle links are in alignment.

10. In a casket lowering device having parallel bars, a temporary support member having a portion thereof rotatably mounted upon one of said bars, a rock shaft extending parallel to and below such one parallel bar, and toggle links connecting said rock shaft with another portion of said temporary support, said links lying between said rock shaft and said one parallel bar when said temporary support extends downwardly in withdrawn position, said links being in alignment when said temporary support is in horizontal operative position, there being means present re-

stricting the pivotal movement of one link with respect to the other when said links are in alignment.

11. In a casket lowering device having parallel longitudinal bars connecting by transverse bars with corner posts receiving said bars and wherein the longitudinal bars have belts connected from one bar to the other, a means for temporarily supporting a casket prior to the same being supported and lowered upon said belts, said means comprising temporary supports mounted so as to rotate freely on said longitudinal bars, rock shafts extending parallel to and below said longitudinal bars and being supported in said posts, toggle links connecting said rock shafts with said temporary supports said toggle links having restricted pivotal movement so as to sustain a load upon said temporary supports and a lever operable to actuate said rock shafts and said temporary supports in unison.

DAVID A. COLLINGS.
